DESIGN FOR A TRANSPARENT COMB

Lewis S. Utley, Forest Hills, Long Island, N. Y., assignor to Columbia Protektosite Co., Inc.,
Carlstadt, N. J., a corporation of New Jersey

Application December 4, 1946, Serial No. 135,241

Term of patent 7 years

(Cl. D86—8)

To all whom it may concern:

Be it known that I, Lewis S. Utley, a citizen of the United States and resident of Forest Hills, Long Island, in the county of Queens and State of New York, have invented a new, original, and ornamental Design for a Transparent Comb, of which the following is a specification, reference being had to the accompanying drawing, forming a part thereof, and of which Fig. 1 is a view in side elevation of a transparent comb embodying my new design; Fig. 2 is a bottom plan view thereof; Fig. 3 is a view in end elevation; Figs. 4, 5, and 6 are sectional views taken respectively on lines 4—4, 5—5, and 6—6 of Fig. 1.

The dominant features of the design reside in the portions shown in full lines.

I claim:

The ornamental design for a transparent comb, substantially as shown and described.

LEWIS S. UTLEY.
